UNITED STATES PATENT OFFICE.

AUGUST L. SEGELHORST, OF WHITTIER, CALIFORNIA, ASSIGNOR TO STANDARD OIL COMPANY, OF SAN FRANCISCO, CALIFORNIA, A CORPORATION OF CALIFORNIA.

PUMPING APPARATUS.

Application filed November 8, 1924. Serial No. 748,614.

My invention relates to apparatus especially adapted for operating deep well pumps, such as those used in oil wells.

The principal object of my invention is to provide an apparatus by which a relatively long stroke, say from six to ten feet, or even more if desired, may be imparted to the well pump piston. The advantages of a long stroke, in increasing efficiency and decreasing maintenance costs, on sucker rods and valves, are well known in the oil-production industry.

Another object of my invention is to provide a simple apparatus, of comparatively small cost, which is adapted for use in connection with the ordinary power equipment usually associated with oil wells, for both drilling and pumping. Thus my apparatus may be applied either to a new well or to one already on production, without necessitating the abandonment of the installed machinery. For example, I make use of the usual band-wheel shaft and crank for transmitting the power to my apparatus, and even the walking-beam may be utilized in a manner to be later described.

Other advantages of my apparatus are that the power is applied gradually to the sucker rods, increasing from each end of the stroke to a maximum at the mid-stroke position, thus minimizing the reversal strains; that the apparatus lends itself readily to the use of a counter-weight for partially counter-balancing the sucker rods and well pump plunger; that the power is applied to the sucker rods in a true vertical direction, avoiding all bending of the polisher rod; and that simple means are provided for automatically absorbing sudden strains, due to sticking of the pumps, to prevent damage to the working parts.

Other objects and advantages of my invention will be apparent from the following description of a preferred embodiment thereof. It is to be understood, however, that the form and construction of the apparatus herein illustrated and described may be varied, within the limits of the claims here-to appended, without departing from the spirit of the invention.

With this in view a preferred embodiment of my invention will now be fully described

with reference to the accompanying drawings, wherein:

Fig. 1 is a side elevation of the complete apparatus.

Fig. 2 is a vertical section, enlarged, of the working cylinder.

Fig. 3 is a vertical section, enlarged, of a preferred form of power cylinder.

Fig. 4 is a vertical section, enlarged, of a modified form of power cylinder.

In the drawings, and referring for the moment to Fig. 1 thereof, the reference numeral 1 designates the usual band wheel shaft, carrying the band-wheel 2 and being suitably mounted in its usual position above the derrick floor 3. It is understood that the band-wheel 2 is connected in the usual manner with an engine or other source of power, not shown. 4 is the crank on the end of the band wheel shaft. Said crank is connected by a crank-pin 5, with the piston 6 of a pump cylinder 7. In its preferred form, as shown in Fig. 3, said cylinder is mounted for oscillation at 8 upon a suitable support, which may be one of the sills or beams 3' of the derrick floor 3, and the piston 6 is directly connected with the crank-pin 5. The pump thus formed is single acting, the piston being suitably packed in the end of the cylinder, as shown at 9. A pet-cock 10 is provided for the release of entrapped air.

The function of the pump or power cylinder thus described is to supply fluid under pressure impulses alternating in direction of flow, to a working cylinder having a piston connected with the sucker rods of the well pump. This fluid is preferably a liquid; and may be water, oil, or any other suitable medium for transmitting power from the power cylinder to the working cylinder.

The working cylinder preferably comprises a barrel 11, Fig. 2, mounted within a tubular casing or sleeve 12 and positioned in vertical alignment above the head 13, Fig. 1 of the well casing. Said sleeve 12 is provided with a lower removable section 14, which is preferably connected with the casing head 13 as indicated at 15. The upper end of the sleeve 12 is secured, as by means of hangers 16, to some suitable fixed sup-

port, which may conveniently be the end of the usual walking beam 17, said walking beam being fixed in position and resting upon the headache post 18. The usual pitman 5 rod is, of course, removed.

The polish rod 19, which, as usual, is connected at its lower end with the sucker rods (not shown), extends upwardly through suitable packing 20, Fig. 2, in the closed 10 lower end 21 of the working cylinder, and is provided at its upper end with an eye 22, to which is secured a cable 23. Said cable passes up through the open upper end of said working cylinder, over a sheave 24, Fig. 15 1, mounted at the inner end of the walking beam 17, thence horizontally to another sheave 25 at the outer end of said walking beam, and thence downwardly to a counter-weight 26 slidably mounted upon suitable 20 guides, one of which is shown at 27. A link and hook connection 28 is preferably provided in the cable 23, to permit the ready disconnection of said counter-weight when necessary. The counter-weight is insufficient 25 to completely balance the weight of the sucker rods and well pump plunger, so that said rods and plunger will always return by gravity to their lowermost position.

A piston 29, Fig. 2, is secured upon the 30 polish rod 19 within the working cylinder. Said piston may be of any suitable construction, but is here shown as comprising a series of cup leathers 30 separated by spacers 31, and is secured upon the rod 19 by a set screw 32, and provided with packing 33 to prevent leakage. As a further means of securing said piston upon the rod 19, I may provide a clamp 34 and a spacer 35 extending up to the eye 22 at the upper end of said 40 rod. Access to said piston, for repair, can be had by removing the lower section 14 from the working cylinder, and there should be sufficient space between said lower section 14 and the casing head 13 to give access to 45 the polish rod packing and to permit the usual clamps to be applied to said rod when dismantling the working cylinder.

The working fluid is transmitted from the 50 pump or power cylinder 7 to the working cylinder, and vice versa, by a pipe 36, Fig. 1. The outlet of said pump cylinder is at its lower end, as at 37, Fig. 3, and leads through the hinge 8 and into the pipe 36 by a swivel joint 38. At its other end the pipe 36 is connected at 39, Figs. 1 and 2, with the lower section 14 of the working cylinder, and the working fluid is thereby led into said cylinder below its piston, when said piston is at the lower end of its stroke. A pet-cock, indicated at 40 in Fig. 1, is provided in the 55 lower end of the working cylinder to permit the escape of entrapped air when the system is being filled with the working fluid.

There are no valves in the connecting pipe 60 36. Power is transmitted directly from the

power piston 6 to the working piston 29 by the column of liquid, so that, as the power piston moves down, the working piston moves up, and vice versa, the downward or return stroke of said working piston being 70 caused by the weight of the sucker rods and the well pump plunger, assisted by the suction of the power piston. The two cylinders obviously have the same capacity, but by making the working cylinder longer and of 75 less diameter than the power cylinder, the sucker rods can be given a relatively long stroke as compared with the stroke of the band wheel crank pin 5. Thus the customary or existing band wheel assembly, with its short-throw crank, may be used to produce 80 a long stroke movement of the sucker rods.

To provide for filling the system with working fluid a stand-pipe 41, Fig. 1, is connected, through a shut-off valve 42, with the 85 pipe 36. Said stand-pipe, if water is used for the working fluid, may have a connection (not shown) with a water supply system, or it may connect with any suitable reservoir or filling means, not shown, as desired, but said stand-pipe must be above the level of the top of the power cylinder or the bottom of the working cylinder, whichever is the higher. An air compression chamber 43 is also 90 connected with the pipe 36 through a shut-off valve 44, and may be provided with a pressure gauge 45 if desired.

In filling the system initially, the power piston 6 is raised to the top of its stroke, the working piston 29 being allowed to remain in its lowermost position. The working fluid is then admitted from the stand-pipe 41 through the valve 42, and fills the entire system except a portion of the air chamber 43, the pet-cocks 10 and 40 being 100 opened to allow the escape of air from the power and working cylinders respectively. The filling valve 42 is then closed, and the power piston moved downwardly, to compress the air within the chamber 43 to the 105 desired pressure, or until the working piston begins to lift. The air chamber valve 44 is then closed, the power piston raised again to its upper position, and additional working fluid admitted through the filling valve 42 to again fill the cylinders and piping. Said filling valve is then closed, the air chamber valve 44 is opened, and the system is ready 110 for operation. By this means I avoid the necessity of supplying outside pressure to the air chamber 43, and yet can raise the pressure therein sufficiently to provide a cushion to prevent the working piston from pounding on the bottom of its cylinder. As an additional precaution against such pounding, a cushioning spring 29', Fig. 2, may be provided at the lower end of the working piston 29.

A safety storage tank 45' is also provided, as shown in Fig. 1, capable of holding the 115

entire amount of fluid contained in the system. Said tank is connected with the pipe 36 by two branches 46 and 47. In the former is an automatic relief or blow-off valve 48, and in the latter is a shut-off valve 49, which is normally closed. If the pressure in the system rises to an abnormal or dangerous point, due to sticking of the well pump plunger or other causes, the working fluid escapes through the automatic relief valve 48 and the branch 46 into the storage tank 45, thus preventing damage to the system. Said fluid may be used to refill the system, through the valve 49 and the branch 47, thus avoiding waste or loss of fluid.

In order to automatically compensate for the small amount of working fluid that may escape past the pistons or packings or through other leaks during the operation of the apparatus, I provide a reservoir 50, Fig. 1, preferably adjacent to and supported by the working cylinder, and having a filling aperture or plug 51 and a gauge glass 52. Connected with the lower end of said working cylinder is a member 53 having a bore of two different diameters as shown in Fig. 2, the larger end 54 being in communication with said working cylinder. A plunger 55, having end portions of different diameters corresponding to and fitting within said differential bores, is slidable therein and is normally retained by a spring 56 at the end of its travel nearest said working cylinder. The smaller bore 57, which acts as a pump cylinder, is connected by a pipe 58 and an inlet check valve 59 with the reservoir 50, as shown in Fig. 1, and by a pipe 60 and an outlet check-valve 61 with the lower portion of the working cylinder, as shown in Fig. 2.

When the working fluid is put under pressure, to raise the working piston, the differential piston or plunger 55 is forced outwardly, against the action of its spring 56, and thereby pumps a small amount of working fluid into the system through the pipe 60, and when the pressure is reduced, on the down stroke of the working piston, said plunger 55 is returned by its spring 56, drawing a fresh charge of working fluid from the reservoir 50 into the smaller bore or cylinder 57, ready to be pumped into the system at the next pressure stroke. Thus at each up stroke of the working piston, a small amount of working fluid is forced into the system to replace that lost by leakage.

To prevent an over-supply of fluid in the system, with consequent blowing off of the automatic relief valve 48, a return connection 62, Fig. 1, of restricted capacity, is made between the upper portion of the working cylinder and the reservoir 50. This connection, which is uncovered by the working piston at the upper end of its stroke, not only allows any excess fluid to return to the auxiliary reservoir 50, but also serves to

limit the upward movement of the working piston.

In Fig. 4 of the drawings, I have shown a modified form of pump or power cylinder with an easily adjustable crank throw to vary the length of stroke. In this modification, the power cylinder 63 is stationary, and secured to the derrick floor by any suitable means, not shown. The pump or power piston 64 may be of any suitable and well known type, the up-stroke being the power or compression stroke. Said piston is carried upon a rod 65, slidable in a comparatively long guide 66 in the upper cylinder head 67 and suitably packed as at 68. A connecting rod 69 connects said piston rod 65 with a crank pin 70, which extends from a block 71 slidable radially in a slot 72 formed in a guide member 73 secured to the usual crank 74 in any suitable manner, as by means of a bolt 75. A screw 76, having a lock nut 77, is provided for holding the block 71 in its position and for adjusting it, radially of the crank, to vary the length of the stroke. The crank 74 is carried upon the end of the band wheel shaft 1 as in the previously described form. The outlet 78 of the cylinder 63 is at its top, and is connected directly with the pipe 36, no swivel connection being needed. A valve controlled by-pass 79, to permit the escape of entrapped air as well as to allow the piston 64 to operate idly, may be provided if desired.

Obviously, the crank throw adjusting means above described may be used with the form of power cylinder shown in Figs. 1 and 3, which has the advantage of being capable of lying down flat upon the derrick floor out of the way, when it is necessary to use the band wheel shaft for other purposes.

It will be seen that my apparatus can be applied readily to existing well-rigs of the ordinary type, and when so installed, provides means for obtaining a much longer stroke on the sucker rods than is possible under the usual conditions. It also lends itself readily to effective counter-balancing of the sucker-rods, and provides a straight pull, preventing any bending of the polish rod. It should be noted, moreover, that there are no valves in the pipe 36 connecting the power cylinder with the pumping cylinder, so that there is a minimum number of moving parts to require attention or repair.

I claim:

1. In a well-pumping apparatus, a fluid power-transmitting system comprising a power cylinder, a piston operable therein and connected with a source of power, a working cylinder, a piston operable therein and connected with the well pump, and a connection wholly independent of the pumped well fluid for conducting the working fluid between said cylinders; a reservoir

- for containing an additional supply of working fluid; and means for automatically supplying additional working fluid from said reservoir to the system during its operation.
5. 2. In a well-pumping apparatus, a fluid power-transmitting system comprising a power cylinder, a piston operable therein and connected with a source of power, a working cylinder, a piston operable therein and connected with the well pump, and a connection for conducting the working fluid between said cylinders; a reservoir; means for automatically permitting the escape of the working fluid from the system into said reservoir under abnormal pressure conditions; and means for restoring said fluid from said reservoir to said system at will.
10. 3. In a well-pumping apparatus, a fluid power-transmitting system comprising a power cylinder, a piston operable therein and connected with a source of power, a working cylinder, a piston operable therein and connected with the well pump, and a connection for conducting the working fluid between said cylinders; means for introducing fluid into said system; a pressure chamber connected with said system; and a valve for closing the pressure chamber connection to trap the pressure in said chamber.
15. 4. In a well pumping apparatus, a working cylinder; a piston operable therein and connected with the well pump for operating the latter; means for supplying working fluid under fluctuating pressure to said cylinder to operate its piston; a reservoir adapted to contain an additional supply of the working fluid; means for automatically supplying fluid from said reservoir to the working fluid system during its operation; and means for returning excess working fluid from the system to said reservoir.
20. 5. In a well pumping apparatus, a working cylinder; a piston operable therein and connected with the well pump for operating the latter; means for supplying working fluid under fluctuating pressure to said cylinder to operate its piston; and an auxiliary pump independent of the working piston and operated by the pressure variations in the working fluid for supplying additional fluid to the working fluid system.
25. 6. In a well pumping apparatus, a working cylinder; a piston operable therein and connected with the well pump for operating the latter; means for supplying working fluid under fluctuating pressure to said cylinder to operate its piston; an auxiliary pump for supplying additional fluid to the working fluid system; and means for operating said auxiliary pump comprising a cylinder and a piston operable therein and exposed to the varying pressure of the working fluid.
30. 7. The combination with an oil-well rig comprising a band-wheel shaft having a crank thereon, a walking-beam, and a well-pump; of means for supporting said walking-beam in a stationary substantially horizontal position; a fluid pump connected with an operated by said band-wheel crank; a working cylinder positioned in alignment with the well-pump; a supporting connection between said cylinder and said walking beam; a piston operable in said cylinder and connected with the well-pump plunger; a cable secured to and extending upwardly from said piston; guide sheaves mounted upon said walking-beam for directing the end portion of said cable downwardly; a movable counterweight secured to the downwardly directed end portion of said cable; and means for conducting the working fluid between said fluid pump and said working cylinder below its piston.
35. In testimony whereof I have signed my name to this specification.

AUGUST L. SEGELHORST.
